UNITED STATES PATENT OFFICE.

RALPH M. SHARAF, OF NEW YORK, N. Y., ASSIGNOR TO R. M. SHARAF MACHINE CO., OF BOSTON, MASSACHUSETTS, A CORPORATION OF MASSACHUSETTS.

VARIABLE-WIDTH TWO-NEEDLE SEWING MACHINE.

Application filed April 19, 1916, Serial No. 92,140. Renewed July 13, 1921. Serial No. 484,506.

To all whom it may concern:

Be it known that I, RALPH M. SHARAF, a citizen of the United States, and a resident of the city of New York, borough of the Bronx, in the county of Bronx and State of New York, have invented a new and Improved Variable-Width Two-Needle Sewing Machine, of which the following is a full, clear, and exact description.

10 This invention relates to sewing machines and has particular reference to two needle machines.

Among the objects of the invention is to provide a sewing machine having two needles and provision for causing the needles to make independent zigzag stitches.

Another object of the invention is to provide means to adapt the needles of a two needle machine while operating in forming zigzag stitches to co-operate with the hooks of a pair of shuttles or hooked loopers mounted for rotation on vertical axes.

A still further object is to provide mechanism in a lace sewing machine for attaching either or both edges of the lace to the cloth and at the same time trim the cloth adjacent the stitches and fold the raw edge of the cloth formed by this trimming so as to produce along the seam or row of stitches a perfectly finished edge.

Another object of the invention is to provide an attachment for sewing machines for attaching lace to cloth, the edge of the lace so attached being secured by a zigzag stitch and at the same time folding the edge of the cloth which is overwhipped by the zigzag stitches.

A still further object of the invention is to provide a sewing machine having facilities for sewing insertion on cloth by zigzag stitches along the edges of the lace, along either straight or curved patterns, the cloth being cut simultaneously with the operation of the stitching mechanism along the rows of stitches and means being provided to fold over the raw edges of the cloth within the several rows of zigzag stitches to produce only finished seams.

With the foregoing and other objects in view the invention consists in the arrangement and combination of parts hereinafter described and claimed, and while the invention is not restricted to the exact details of construction disclosed or suggested herein, still for the purpose of illustrating a

practical embodiment thereof reference is had to the accompanying drawings in which like reference characters designate the same parts in the several views, and in which—

Figure 1 is a front elevation of the principal parts of the mechanism; 60

Figure 2 is a bottom plan view of the same;

Figure 2^a is a detail view indicating more particularly the right and left screw adjustment means for the shuttle mechanism; 65

Figure 3 is a plan view of the shuttle end of the bed with the throat plates removed to disclose the relation of the rotary shuttles to the feeding mechanism; 70

Figure 4 is a vertical transverse section of the same on the line 4—4 of Fig. 3;

Figure 5 is an enlarged front elevation of the needle bar and the means for controlling the action of the needles toward and from each other in making the zigzag stitches; 75

Figure 5^a is a detail plan view of the driving mechanism;

Figure 6 is a vertical transverse sectional detail on the line 6—6 of Figure 8; 80

Figure 7 is a fragmentary view in elevation looking toward the right of Figure 5, parts being in section to show the construction; 85

Figure 8 is a horizontal section of the needle holders and thimble on the line 8—8 of Figure 5;

Figure 9 is a vertical sectional view on the line 9—9 of Figure 1 and indicating particularly the stitch adjustment auxiliary to the differential feed mechanism; 90

Figure 10 is a perspective detail indicating the relation of the stitching device to the edge of the lace being attached to the cloth and also indicating parts of the cloth cutting means and the folding guide; 95

Figure 11 is a diagram indicating the relation of the shuttle hook and thread catcher to the needle at the moment the needle reaches its lower limit of movement, these parts referring to the shuttle on the right, or as indicated in the upper part of Figure 3;

Figure 12 is a diagram of the same when the needle has been lifted and the thread is to be transferred from the thread catcher to the shuttle hook; 105

Figure 13 is a perspective detail approximately at right angles to Figure 11 and 110

showing the relation of the shuttle hook to the thread catcher;

Figures 14, 15 and 16 are views corresponding respectively to Figures 11, 12, and 13, but referring to the shuttle at the left or as shown in the lower portion of Figure 3;

Figure 17 is a vertical transverse section of the work, indicating diagrammatically the relation of the cloth folding guide to the zigzag stitches; and

Figure 18 is a diagram in plan of the throat plates adjustable toward and from each other, and the associated parts, including a filler plate movable at right angles to the direction of adjustment of the throat plates.

Referring now more particularly to the drawings, I show a sewing machine bed 20, head 21 and usual driving mechanism, including a belt wheel 22 of any suitable or approved construction and provided with a differential feed two needle mechanism, preferably of the type disclosed and claimed 25 in my co-pending application, filed October 24, 1916, Serial No. 127,323, Patent No. 1,466,152 dated August 28, 1923. Without going into an unnecessary lengthy description of that mechanism in this case, but in 30 order to give a sufficient understanding thereof for the purpose of covering the new features, I will state briefly that the differential feed mechanism includes a knee yoke 23 (Fig. 2) adjustable to fit the operator's knee by means of set screws 24 acting upon the side wings 25 of the yoke. Said yoke is connected to a gear segment 26 (Fig. 1) suitably journaled upon a bracket 27 and meshing with a pinion 28 secured to 35 a shaft 29 extending rearwardly in a horizontal plane beneath the machine table and having a miter gear connection at 30 with a longitudinal shaft 31 (Figs. 1 and 9), having at its other end a pinion 32 meshing with the double cam wheel 33 fully set forth 40 in the aforesaid application. By reference to Figure 9, sufficient of this mechanism will be comprehended for the purpose of this present case. This mechanism includes a 45 main shaft 34, a countershaft 35, crank connections 36 between the main and counter-shaft, and an eccentric 37 secured upon the countershaft and operating a rocker 38 connected to a rock shaft 39. A pair of radius links 40 are connected at one end at 41 to the relatively movable concentric rock shafts 42 and 43, to the other ends of which are connected independently operated feed dogs (see Figure 4). As fully 50 set forth in the other application referred to, by adjustment of the radius links 40, or rather of the slides 44, connected with them, in the slots 44 of the rockers 38, the effective throw of the rocker, and the extent of rotation 55 of the rock shafts 42 and 43 are varied.

The cam grooves 33' in the cam wheel 33 act through draw bars 45 (Figs. 1, 2 and 9) to throw the adjustable ends of the links 40 up or down. In the position shown in Figure 9, the mechanism is set to operate both feed dogs in unison and in parallel straight lines, the cam slot 33' being ineffective to vary the relation of the link mechanism. In my said co-pending application, the only way to change the length of the stitch was through the actuation of this cam wheel and that to shorten the stitches of one needle, while those of the other needle remained unchanged. In this improvement, however, I provide means for lengthening or shortening the stitches of either needle independently of this differential feed mechanism. To this end I show two pairs of toggle links 46 and 47, the links of each pair being connected by a block 48, being threaded for a screw 49, having its other end journaled for rotation in the opposite block 50 connecting the links of the other pair. The journaled end of the screw is held from endwise movement in the block 50. By the rotation of the screw in one direction or the other by means of a tool introduced through the machine casing at the hole 51, the effective length of the toggle connection between a bar 45 and the corresponding radius link 40 is increased or decreased with a corresponding adjustment of the slide 44' toward or from the axis of the rocker. It will be understood that this specific description of the means for adjusting the effective throw of one link 40, will be applicable to the mechanism for adjusting the operation of both of the feed dogs and the length of the stitches.

The type of machine illustrated includes 105 a pair of hooked loopers or rotary shuttles 52 and 53 (Fig. 3) journaled for rotation around vertical axes on the right and left sides respectively of the line of the work. These shuttles are rotated in the same direction and have hooks 54 and 55 respectively to receive the thread from the needles 57 and 58 (Figs. 4, 5, 6 and 8). The rotation of the shuttles is effected as heretofore 110 by means of miter gears 59 connecting vertical and horizontal shafts 60 and 61, the latter being driven at high speed through gears 62 (Fig. 1) from the countershaft 35. The independently controlled feed dogs are indicated at 63 and 64 (Figs. 3, 4 and 18), the same being connected to feed bars 65 and 66 respectively connected as above intimated to the concentric rock shafts 42, 43 and the effective lift of the dogs is controlled as in my said co-pending application, 115 by means of a lifting arm 67 (Fig. 4).

The two shuttles and driving means therefor are mounted for adjustment longitudinally of the machine bed toward and from each other to accommodate the same 120

to rows of stitches of narrower or greater widths between. The shuttles and their vertical shafts 60 are mounted upon adjustable blocks 68 and 69 (Fig. 3) having slots 70, 5 into which binding screws 71 project. The feed bars 65 and 66 are likewise adjustable for sliding movement toward and from each other along their respective rock shafts, and the feed dogs carried thereby maintain their 10 proper relation to the throat plates 72 and 73 connected by screws 74 (Fig. 18) or their equivalent to their respective blocks 68 and 69. The screws 74 enter tapped holes 74' in the blocks. When the throat plates are 15 thus moved apart, the opening that would be caused thereby may be filled by a tapered filler plate 72' movable by the operator rearwardly at right angles to the direction of movement of the throat plates, (see Figure 18).

I will now describe the means for adjusting the blocks toward and from each other. 75 (Figs. 1, 2 and 4) indicates a plate located horizontally below the high speed shaft 61. In this plate are journaled the screws 71 above described. To the lower end of each of these screws is secured a gear 76. These gears are all of the same size and a master gear 77 is arranged within 30 the center of the group and meshes with all of them. A hand wheel 78 or its equivalent is connected by a spindle 79 to the master gear 77, whereby a rotation of the spindle and master gear in either direction will 35 cause a corresponding rotation of all of the binding screws 71 to loosen or tighten the same simultaneously. When the screws are thus loosened, the blocks may be adjusted by any suitable means. As shown 40 in Figures 2, 2^a, and 4, I provide front and rear right and left screws 80 and 81 having threaded engagement with correspondingly threaded holes in the front and rear ends of the blocks 68 and 69. Each of the screws 45 is provided at the center with a worm wheel 82, and these two worm wheels mesh with a pair of worms 83 secured upon a horizontal shaft 84 journaled transversely of the machine and having a pinion 85 at its front 50 end meshing with a large gear 86 which is adapted to be rotated by a screw driver or the like applied at 87. By the rotation of this gear 86 and correspondingly rapid rotation of the shaft 84, the worms 83 are 55 both rotated in the same direction simultaneously and the right and left screws 80 and 81 act simultaneously to force the blocks toward or from each other depending upon the direction of rotation of the wheel 86. A scale 88 (Fig. 3) may be arranged 60 at any suitable place to indicate the extent and character of adjustment of these mechanisms. After the adjustment is made, the screws 71 will be tightened to clamp the 65 shuttle mechanisms firmly in place. The

effect of the worms 83, however, is that of a lock for the adjustable blocks.

I will now describe the needle mechanism as it applies to a two needle machine adapted for forming zigzag stitches. In Figure 5 I 70 show a needle bar 89 of tubular form having rigidly but detachably connected to its lower end a thimble 90, the longer axis of which is horizontal and parallel to the main shaft 34 of the machine. The needles 57 and 58 extend through slots 91 and 92 in the bottom of this thimble and are locked in a pair of blocks 93 and 94 fitted in the thimble for sliding toward and from each other. The needles are both moved at the same time toward each other and likewise at the same time away from each other, and as shown in Figures 5 and 8 they occupy their nearest position with the needle bar elevated. Each block 93 or 75 94 has an inward extension 95 and these extensions co-operate with each other to substantially fill the central portion of the thimble. Each of these extensions 95 is provided with a transverse groove 96 along its upper surface and these grooves 96 are so arranged that they preferably coincide or constitute an extension of one another when the needles occupy a position midway between their inward and outward positions. In 80 other words, while Figure 8 shows the 90 needles adjusted toward each other to their maximum, when they are thrown farthest apart the relative positions of the grooves 96 will have changed place in effect. That is to say, the groove 96 at the upper portion of Figure 8 will have moved as far to the right, and the one at the bottom of the figure as far to the left as they now appear to the left and right respectively. The needle bar 89 is 95 adapted to be reciprocated up and down in the usual manner from a crank pin 97 carried by a head 98 on the end of the main shaft through a connecting link 99 connected to a clip 100. Likewise a conventional form of 100 thread take-up 101 is journaled at 102 and is operated by a cam 103 in the head 98. It is to be noted, however, that this thread take-up 101 carries a pin 104 which oscillates a lever 105 pivoted on a horizontal pivot 106 and whose other end has a fork 107 in which 105 is engaged a pin projected at the upper end of the lace feeding bar 108.

Within the tubular needle bar is journaled a spindle 109 for limited rotation, but held from endwise movement with respect to the needle bar by suitable means, as for example, the screws 110, which serve to lock the thimble to the needle bar, the inner ends of these screws extending into a circumferential groove 111 formed in the lower end of the spindle. To the extreme lower end of the spindle are secured a pair of fingers 112 extending parallel to each other on diametrically opposite sides of the axis of the spindle 115 and into the respective grooves 96 of the 120 125 130

needle holders. The needle holders are held from rotation within the thimble by means of a pin 90^a projecting into companion grooves 90^b formed in the lower portions of the extensions 95. Any suitable means may be provided to cause a to and fro rotation of the spindle through a short angle once for each two rotations of the main shaft, whereby, when the spindle is rotated to throw the needle holders outwardly or away from each other, the needles will be caused to enter the cloth to make one stitch at the maximum distance apart. At the next rotation of the main shaft and operation of the needles, they will enter the cloth at the minimum distance apart and thereby two parallel rows of zig-zag stitches will be formed simultaneously. The needle bar, in this instance, is shown provided with a straight vertical groove 113, into which a pin 114 always projects. This pin is carried by the lower end of a lever 115 pivoted at 116 and having at its upper end an inclined slot 117, into which the end 118 of a lever 119 projects. This lever, like the lever 115, is of the first class and is pivoted at 120 on a horizontal axis. The opposite end of the lever 119 is deflected downwardly, forming a nose 121, co-operating with a cam wheel 122 having alternate crests 122^a and dwells 122^b. The number of crests and dwells of this cam wheel is equal to the number of teeth in a worm wheel 123 secured to the shaft 124, upon which the cam wheel is secured. This worm wheel is given a step by step rotation, one tooth for each rotation of the main shaft, by virtue of a single thread worm 125 secured to the main shaft. The worm 125, as will be noted especially in Figure 5, has the peculiarity that only the tail end 125', or the part that leaves the worm gear 123 last, is formed spirally, the major portion of this gear being circumferential only. In other words, with the main shaft rotating as indicated by the arrow on Figure 5, the worm 125 is engaged between two of the teeth of the worm gear 123, holding said gear from movement until the tail 125' of the worm comes into action, causing a rotation of the worm gear and cam wheel 122 through the extent of one tooth.

A spring 126 acts constantly upon the lever 119, tending to throw the nose 121 toward the center of the cam wheel. In the position shown in Figure 5 this nose is occupying one of the dwells of the cam wheel and thereby the lever 115 is held so as to hold the pin 114 with its point projecting through the shell of the needle bar only in the slot 113. In this condition, the needles will make their next down stroke closest together. When the main shaft makes its next rotation, the cam wheel will be moved forward one step, bringing one of the crests 122^a beneath the nose 121, throwing the end 118 downwardly along the slot

117, and forcing the pin 114 inwardly beyond the slot 113 and into a cam slot 127 formed along the spindle 109. The lower end of the cam slot is straight and vertical and registers with the lower end of the straight slot 113 every time the needle bar is in its uppermost position. The longer portion, however, of the cam slot is deflected laterally from the straight slot 113 and when the pin 114 is forced into the cam slot and so held by the action of the gear 125 and intermediate parts while the needles make the next down stroke, the pin acts to cause the rotation of the spindle above referred to with the throwing of the needle holding blocks away from each other (see dotted lines in Fig. 5). When, however, the needle bar is again lifted, on its next up stroke the cam portion of the cam slot co-operating with the pin 114 will return the spindle and needle holders connected thereto, to their position indicated by full lines in Figure 5. On the next down stroke of the needles and on the immediately succeeding upstroke, they keep this position and are so held by friction of the movable parts 93, 94, and 109 (the pin 114 being withdrawn from the cam slot 127). In other words, while I show nothing to positively hold the needles in their nearest position, there is nothing acting thereon at this time to cause them to move from such position until the next succeeding downward stroke, when they are thrown apart again by the action of the pin 114 in the cam slot, and when the needles are in their lowest position the pin acts in the cam slot as a lock, preventing the needles from moving toward each other when down.

I will now describe the means to make the shuttles effective in their co-operation with the needles when the latter are adjusted toward each other and hence remote from the hooks 54 and 55 of the shuttles. By reference to Figures 3 and 4, it will be noted that in the practice of a rotary shuttle machine, the shuttles rotating around vertical axes, the advancing point or hook of each shuttle in an ordinary machine glides closely alongside the needle and catches the thread between the needle and the last stitch formed thereby. This statement presupposes that the needle is reciprocated up and down close to the path of the shuttle hook, but in this case since the needles are caused to approach each other on the alternate down strokes, they are caused to be moved to a material distance away from the paths of the shuttle hooks, in the making of the zigzag stitches. In other words, the shuttles are so adjusted as to correspond to the points of the needles when the latter are most remote from each other. For operation at this time, I provide some suitable means auxiliary to the shuttle hooks to catch the thread and transfer the

same laterally to the shuttle hooks. The means I employ for this purpose are what I call a pair of thread catchers 128 and 129. Each of these members is shown as in the nature of a lever of the first class pivoted on pivots 130, the axes of which are parallel to and just above the high speed shaft 61, the active points of the thread catchers being on the longer arms of the levers. These 10 points occupy a position normally back of the vertical plane of both needles, (see Figure 4) and are so held by suitable springs 131 connected to the levers above their pivots. At 132 and 133 I show a pair of cam 15 wheels mounted upon a single shaft 134 rotated continuously from one of the other longitudinal shafts, as for example the countershaft 35 as through gears 135, (see Figures 1 and 2). Each of these wheels 20 132 and 133 has a peripheral tooth or projection 136 which is timed to co-operate with the shorter end of the adjacent thread catcher at the point shown at 137 when the needles are down on that stroke that they 25 are closest together. Both of the points then of the thread catchers 128 and 129 co-operate with the needles inwardly with respect to the thread in substantially the same manner that the shuttle hooks co-operate 30 with the thread at the other down stroke of the needles, as above described. The action of the projections 136 on the thread catchers, against the force of the spring 131, is of brief duration and consequently the mechanism 35 is so timed that when the thread catchers catch the threads and transfer the loose portions thereof laterally, the shuttle hooks traveling in their regular order receive the loose portions of the threads from the thread 40 catchers just before the springs 131 throw the thread catchers back to their normal position, where they remain until the wheels 132 and 133 make one more rotation and the needles have been given a second subsequent 45 downward reciprocation. Stop means as a pin 137' may be arranged, if desired, to limit the throw of each thread catcher under the force of the spring 131 acting thereon, so as to relieve the friction which might result 50 from the shorter end of the lever being pressed against the circular periphery of the wheel carrying the projection 136 adjacent thereto. Figures 11 to 16 indicate the action of these several thread catchers. In Figures 55 11 to 13, I show the thread catcher 128 which moves from normal position in a direction to meet the approaching shuttle hook. Figure 11 shows the position just at the time the thread catcher is to be actuated. Figure 12 indicates the position after the thread catcher has been thrown 60 forward and the shuttle hook has advanced to the position to receive the thread therefrom, and the point of the shuttle hook will 65 enter the loose loop of the thread before the

thread catcher is returned to normal position. Figure 14 is a diagram corresponding to the shuttle hook 55, the direction of movement of which is the same as that of the thread catcher 129, but otherwise the effect 70 is the same as described in connection with Figures 11 and 12.

This machine is designed with particular reference to the sewing of lace or insertion on cloth by simultaneous parallel rows of 75 stitches and the cutting out of the cloth beneath the lace between the stitches in a single operation, in a manner similar to the action of the machine above referred to and covered by the claims of my application Serial No. 127,322. I provide, however, for the adjustment of the shuttle mechanism, as above described, to accommodate the machine to narrower or wider lace. The lace feeding device indicated in Figure 1 also 80 is preferably made adjustable as indicated at 138 to accommodate the width of lace to be used at any particular time. The needle holding thimble 90 disclosed herein, is not adjustable in length and for the purpose 85 of adapting this type of needle holder to a machine having adjustable shuttle mechanism and adjustable lace feeding mechanism along with the adjustable cloth cutting devices, I may provide a set of different sizes 90 of needle holders, since they are easily removable and interchangeable with respect to the needle bar. By my copending application, Serial No. 92,141, filed of even date herewith, I disclose specifically the means 95 for adjusting the lace feeding devices and cloth cutting devices, as well as the needle holders.

Figure 10 is a fragmentary view, showing the action of the needle mechanism, cloth folding, and cloth cutting devices along one edge of a piece of lace. The cloth is shown at C and the lace at L, the lace selvage edge thereof being indicated at Z. The figure indicates the action of a cutting blade 139 slitting the cloth parallel to the line of the movement of the cloth just ahead of the action of the needle, and at 140 is shown a cloth folding guide projecting downwardly 105 in a vertical plane between the vertical planes of the cutting blade and the needle, and with respect to the line of movement 110 of the cloth. The guide 140 likewise is between the cutting blade and the needle. This guide bears against the raw edge of 115 the cloth just previously formed by the cutting device and folds the same downwardly through about 90 degrees, as shown at c. This folding action to the extent just stated takes place between the vertical planes outlined by the needle while making its zigzag 120 stitches (see also Fig. 17). In other words, the action of the guide 140 is such as to fold or hold the raw edge of the cloth outside of the line of action of the needle or 125 130

remote from the opposite needle while it is making its down stroke closest to the opposite needle. During this down stroke, the needle passes through the lace only. On 5 the next down stroke of the needle, it enters only the cloth from the outside of the lace selvage (see Figure 10), and the thread on the next up stroke completes the folding of the edge *c* of the cloth up against the body 10 of the cloth, where it occupies a position beneath the selvage of the lace, and thereby there is formed a neat, finished seam by virtue of the zigzag stitching and the overwhipping of the thread, the overwhipping including the fold of the cloth, as well as 15 the lace selvage. It will, of course, be understood that this action of the zigzag stitching and the cloth trimming and seam finishing devices, is applicable to the sewing 20 of lace with the use of one needle only, as well as with two needles as contemplated by this particular machine, and hence I do not wish to be limited in this respect to a two needle machine. Figure 17, however, 25 indicates the action of the two needle devices in the sewing of both edges of the lace to the cloth and cutting out the cloth *c'* between the two stitches in the same operation.

30 Since this machine is designed for making parallel seams or rows of stitches in either straight or curved lines, according to the design of the pattern being worked, and the curvature to the right or to the left of the 35 work is effected automatically by the movement of the operator's knee in a corresponding direction to accelerate the feeding mechanism of the curve having the shorter radius, I provide an automatic indicator to assist 40 the operator in regulating the variable feed mechanism precisely in accordance with the variation in curvature of the pattern. A suitable means for this purpose includes an indicator pointer 141 (Fig. 1) carried by 45 the lower end of an arm 142, pivoted at 143 at the top of the head. A link 144 leads from the point 145 intermediate the ends of the arm 142 to a wrist pin 146 connected to a crank disc 147, or its equivalent, connected 50 to a shaft 148 having at its other end a pinion 149 (Fig. 9) driven in turn from a horizontal shaft 150 having miter gear connection at 151 with a vertical shaft 152, to the lower end of which is connected a wheel 153 55 shown as a belt wheel over which operates an endless belt 154 driven from a wheel 155 mounted upon the axis of the double cam wheel 33. The gears and connections, just described, are so arranged and the relation 60 of the parts is so designed that the pointer 141 should always lie directly over the gage mark of the pattern or design being worked, irrespective of the deflection thereof to one side or the other from the median line of 65 operation of the machine. By the term gage

mark as used herein, it may be explained that in the practice of this invention, the only outline or mark required to guide the operator may be of a simple or single line nature, the same corresponding to the median line of the work or the line midway between the two lines of stitches. With a mark of this character formed in any manner upon the cloth to which the lace is to be applied, the operator has but to apply one end of the lace at the proper position at one end of the mark and then by so manipulating the indicator 141 as to be maintained in position over the mark, the lace will be automatically applied to the cloth in 70 the manner set forth herein without any other special care of the operator. This description relates, of course, to the application of lace in the formation of curved or irregular patterns. Obviously the lace 75 might be inserted in a piece of cloth along straight courses or designs of a simpler nature without the necessity of applying or following any gage mark. In other words, if the design of the pattern stamped or 80 otherwise placed upon the fabric should happen to be at any time on the right side, for instance, of said median line, the operator through the knee controlled mechanism, 85 will adjust the indicator until the pointer lies over the mark and the operation incident to this adjustment will automatically 90 change the differential feed mechanism to effect the desired automatic curvature of the work. Nearly all of this indicating mechanism may be housed within the machine 95 head and hence occupies the least amount of available space around the machine. It will be noted that this indicator pointer 141, because of the connections above described, is 100 always immediately available by the operator to disclose by its reference to the median line of the machine's work the precise condition or adjustment of the differential feed 105 mechanism. That is to say, the operator 110 preparatory to starting an operation may not know precisely the proper position for the knee, and if the machine be started with the feed mechanism improperly adjusted a fault will occur in the work, whereas by the 115 aid of the indicator the feed mechanism will always be properly adjusted, not only for starting the operation, but for continuing the work.

With the rotary shuttles mounted for rotation around vertical axes, which after adjustment has been made will be regarded as fixed axes, it will be appreciated that they may be operated much more closely together 120 relatively than if they were caused to rotate around horizontal, transverse axes. It is to be noted also that whether I use one or more needles, the needle bar is a single element 125 caused to reciprocate always in the same vertical line, and that in the making of zigzag 130

stitches, the needle or needles are caused to shift laterally with respect to the needle bar, and the needles, as well as the needle bar, are always reciprocated in vertical lines.

5 I claim:

1. In a sewing machine, the combination of a needle bar, means to reciprocate the needle bar continually along the same axis, a needle holder carried by the needle bar, means to shift the needle holder laterally with respect to the axis of the needle bar, a needle carried by the needle holder with its axis parallel to the axis of the needle bar, and means including a looper rotated 10 around a fixed vertical axis and co-operating with said needle to form a row of zig-zag lock stitches.

2. In a sewing machine, the combination of a tubular needle bar, means to reciprocate the needle bar, a needle holding thimble fixed to the lower end of the needle bar, a pair of needle holders mounted in the thimble for reciprocatory movement toward and from the axis of the needle bar in a rectilinear line, a pair of needles connected to the respective holders, means acting between the needle holders and the thimble to maintain the needles with their axes parallel to the axis of the needle bar, a rotary spindle 25 journaled in the center of the needle bar and engaging at its lower end the upper surface of both of said needle holders, said needle holders being provided at their portions engaged by said spindle with transverse slots 30 at right angles to the rectilinear movement of said needles, a pair of diametrically opposed fingers projecting from the end of the spindle into direct engagement and co-operation with the respective slots of said 35 needle holders, and means to cause a rotary oscillation of the spindle during reciprocations of the needle bar, whereby said fingers will cause simultaneous lateral movement of the needles toward and from each other, the rectilinear movement of said needles being equal to the length of the space bounded by lines at right angles to the rectilinear movement of said needles and passing through the centers of the fingers at their 40 extreme positions.

3. In a sewing machine, the combination of a reciprocating tubular needle bar, a rotary spindle journaled in the needle bar, means to hold the spindle from endwise movement with respect to the needle bar, a pair of needle holders carried by the lower end of the needle bar for reciprocation therewith, a pair of needles fixed to the needle holders and movable with the needle holders laterally with respect to the axis of the needle bar, the needle bar and spindle therein being provided with longitudinal registering slots, one of said slots being straight and the other cam shaped, and

means projecting into said slots to cause a 65 rotary oscillation of the spindle during reciprocations of the needle bar, and connections between the spindle and said needle holders to cause a corresponding lateral movement of the needles. 70

4. The combination of a reciprocating needle bar, a needle carried by the needle bar for reciprocation therewith and shiftable laterally with respect to the axis of the needle bar, a rotary member associated 75 with the needle bar and reciprocating therewith, the needle bar and rotary member being provided with registering longitudinal slots, one of the slots being straight and the other cam shaped, means including a 80 pin movable into the slots toward the center of the needle bar during reciprocations thereof to cause a rotary oscillation of the rotary member, and means connecting the rotary member to the needle to cause a corresponding lateral movement of the needle. 85

5. In a sewing machine, the combination with a main shaft, a tubular needle bar and connections between the shaft and the needle bar to reciprocate the latter during each rotation of the shaft, said needle bar having a straight longitudinal slot, of a rotary spindle journaled in the needle bar and having a cam slot formed therein registering with the straight slot, a pin projecting into the needle bar slot, a pair of needle holders carried by the needle bar, a pair of needles fixed to the respective holders and movable therewith toward and from each other, the needles being closest together during one rotation of the main shaft and reciprocation of the needle bar, and means acting upon said pin forcing it into the cam slot during the next rotation of the main shaft and thereby causing the needles during the accompanying reciprocation thereof to operate farthest apart. 95 100 105

6. In a zigzag lock stitch sewing machine, the combination of a reciprocating needle bar, a needle connected to the needle bar and movable bodily laterally toward and from the axis thereof during the reciprocations of said bar, a hooked looper mounted for rotation around a fixed axis parallel to the needle and toward and from the hook of which the needle is movable, and means co-operating with the needle to catch the thread and transfer it to the hook of the looper during that reciprocation of the needle when remote from the looper. 110 115 120

7. In a zigzag lock stitch sewing machine, the combination of a hooked looper rotating around a fixed vertical axis, a reciprocating needle bar having its axis parallel to the axis of the looper, a needle holder movable toward and from the axis of the needle bar, a needle fixed to the needle holder with its axis between and parallel to the axes of the

needle bar and the looper, and means co-operating with the needle to catch the thread and transfer it to the looper hook when the needle is remote from the looper.

5 8. In a lock stitch sewing machine, the combination of a pair of hooked loopers mounted for rotation around parallel vertical axes, a reciprocating needle bar having its axis between and parallel to the axes of 10 the looper, a pair of needles, a pair of needle holders carried by the needle bar and to which the needles are respectively fixed with their axes parallel to the axis of the needle bar, means acting upon the needle holders to 15 move them apart for direct co-operation with the looper hooks at one reciprocation of the needle bar and to cause them to be closer together and remote from the looper hooks at the next reciprocation, and means 20 co-operating with the needles during the latter mentioned reciprocation to catch the threads and transfer the same to the looper hooks.

9. In a sewing machine, the combination 25 of a reciprocating needle bar, a needle, means to connect the needle to the needle bar and hold it with its axis parallel to the axis of the needle bar, means acting through said connecting means to shift the needle laterally toward and from the axis of the needle bar during the alternate reciprocations, a hooked looper mounted for rotation around a fixed axis parallel to the needle, the hook of the looper co-operating directly with the 30 needle at one reciprocation, and means including a normally stationary member having a point movable into co-operation with the needle at the next reciprocation to catch the thread and transfer the same to the 35 looper hook.

40 10. In a two needle zigzag lock stitch sewing machine, the combination of a pair of hooked loopers mounted for rotation around parallel fixed axes, a needle bar reciprocating with its axis between and in fixed 45 relation to the axes of the loopers, a pair of needles reciprocating with the needle bar, means to hold the needles in spaced relation for direct co-operation with the looper hooks at one reciprocation and to move them into closer relation to each other remote from the looper hooks at the next reciprocation, a pair of thread catchers co-operating with the needles when the needles are 50 remote from the loopers to catch the threads thereof and transfer the same laterally to the looper hooks, means holding the thread catchers stationary when the looper hooks co-operate directly with the needles, and 55 means accurately timed with the looper driving means to cause the operation of the thread catchers during the alternate reciprocations as aforesaid.

60 11. In a two needle sewing machine, the

combination of a pair of hooked loopers, 65 means to rotate the same around parallel axes, a pair of needles reciprocating between the loopers, means to shift the needles toward and from the loopers during the alternate reciprocations of the needles, the 70 axes of the needles lying in the same plane as the axes of the loopers, a pair of pointed thread catchers lying normally at one side of said plane and idle while the needles are reciprocated close to the loopers for direct 75 co-operation with the looper hooks, and means driven from the looper driving devices to act upon the thread catchers to cause the points thereof to cross said plane into co-operation with the needles at that reciprocation of the needles when remote from the loopers to catch the threads thereof and transfer the same laterally to the looper hooks.

80 12. In a two needle lace sewing machine, the combination of a pair of hooked loopers mounted for rotation around parallel axes, means to adjust the loopers toward or from each other for the accommodation of narrower or wider lace, a pair of needles reciprocating between the loopers and movable during alternate reciprocations toward each other remote from the looper hooks and away from each other into direct co-operation with the looper hooks, and means movable transversely to the plane of the needles 90 into co-operation with the needles while making their reciprocation remote from the loopers, for transferring the thread laterally to the looper hooks.

95 13. In a zigzag lock stitch sewing machine, the combination of a hooked looper rotatable around a fixed axis, a needle reciprocating parallel to said axis and shiftable laterally 100 during the alternate reciprocations toward and from the looper, a pivoted thread catcher, a spring acting upon the thread catcher to hold it remote from the needle and idle while the needle is reciprocating in direct co-operation with the looper, and a rotary 110 member acting upon the thread catcher against the force of the spring to cause the point of the thread catcher to co-operate directly with the needle at the next reciprocation thereof to transfer the thread to the looper hook.

115 14. In a two needle zigzag lock stitch sewing machine, the combination of a pair of hooked loopers rotating around parallel vertical axes, a needle bar reciprocating with its axis between and in the same plane as the looper axes, a pair of needles reciprocating with the needle bar, means to shift the needles laterally during said reciprocations and alternately into direct co-operation with the loopers and to points nearer the axis of the needle bar remote from the loopers, a 120 pair of coaxially arranged pivoted thread 125

catchers having points normally at one side of said plane, and rotary means acting simultaneously upon both thread catchers to cause the points thereof to intersect said plane and co-operate directly with the needles when remote from the loopers to transfer the threads thereof laterally to be engaged by the looper hooks.

15. The combination with a sewing machine bed plate and a plurality of parallel binding screws co-operating therewith around fixed axes, of a pair of blocks having slots through which said binding screws project and along which slots the blocks are movable toward and from each other, a pair of loopers journaled for rotation around fixed axes in said blocks, a pair of needles reciprocating between the loopers and movable toward and from each other so as to co-operate directly with the loopers or remotely therefrom, feeding mechanisms pertaining to the several needles and loopers and adjustable with the loopers toward and from each other, and independent thread catchers likewise adjustable through said blocks with the feeding mechanisms and loopers, and serving to transfer the threads from the needles to the loopers when the needles reciprocate remote from the loopers.

30 16. The combination with a sewing machine bed plate having a plurality of binding screws tapped therein, a pair of bearing blocks having slots through which said screws project and along which the blocks are adjustable toward and from each other, means to tighten or loosen all of said screws simultaneously, and pairs of independent loopers, feed dogs, and thread catchers mounted upon said blocks and adjustable therewith toward and from each other.

17. In a two needle sewing machine, the combination of a pair of bearing blocks, means for connecting the blocks and causing the bodily adjustment thereof toward and from each other, said connecting and adjusting means including a pair of parallel screws and means for rotating both screws simultaneously, means to lock the blocks in fixed position after adjustment, a pair of

45 50 loopers journaled for rotation around parallel fixed axes in the several blocks, and feeding mechanism adjustable with each looper toward and from the other.

18. In a two needle sewing machine, the combination with a bed plate, of a pair of bearing blocks adjustable toward and from each other along said bed plate, a pair of throat plates fixed to the respective blocks and adjustable therewith, means acting upon corresponding ends of both blocks simultaneously to cause them to move toward and from each other, means co-operating with the bed plate to lock the blocks in fixed position after adjustment, a pair of rotary

loopers journaled in the respective blocks and each bearing a constant position with respect to the adjacent throat plate in all positions of adjustment, and independent feeding mechanism connected with the several blocks and co-operating with the respective throat plates.

19. In a two needle sewing machine, the combination with a bed plate and a transversely disposed screw shaft journaled beneath the same, of a pair of bearing blocks adjustable toward and from each other along said bed plate, a pair of right and left screws extending between the blocks and tapped into the ends thereof, a worm gear connected to the central part of each screw, a pair of spaced worms secured to the worm shaft and meshing with said worm gears, means to rotate the screw shaft to cause adjustment of the blocks toward or from each other, clamping means co-operating between the blocks and the bed plate to lock the blocks in fixed position after adjustment and at definite distances apart according to a central scale, and independently adjustable looper and feeding mechanism carried by the respective blocks.

20. In a variable width two needle lace sewing machine, the combination of a pair of blocks, means to adjust the same toward and from each other to precise distances, means to lock the blocks in fixed position after adjustment, independent rotary loopers carried by the respective blocks toward and from each other, independent feeding mechanisms carried by the several blocks and adjustable therewith, a throat plate fixed to each block and co-operating with the adjacent feeding mechanism irrespective of adjustment, and a filler plate movable transversely to the direction of the adjustment of the throat plates to fill the gap between them when adjusted away from each other.

21. In a sewing machine, a tubular needle bar and means for imparting reciprocating motion thereto, needle-holding slides carried by the needle bar and adapted to reciprocate transversely thereof in a rectilinear line, a rod extending within the tubular needle bar and held to reciprocate therewith but capable of an oscillatory movement relatively to the needle bar and engaging at its lower end the upper surface of both of said needle holding slides, said needle holding slides being provided at their portions engaged by said spindle with transverse slots at right angles to the rectilinear movement of the said needle holding slides, said rod being provided with diametrically opposite eccentrically located projections in pivotal and sliding direct engagement with the slots of the respective slides, and means for causing said rod to oscillate, the rectilinear movement of said needles being

equal to the length of the space bounded by lines at right angles to the rectilinear movement of said needles and passing through the centers of the fingers at their extreme 5 positions.

22. In a sewing machine, a reciprocating needle bar, a transverse thimble located at the lower end of said bar and provided with a pin extending axially with reference to 10 the needle bar, needle-holding slides movable in said thimble and provided with transverse guide grooves into both of which said pin extends, and means for operating said slides.

15 23. In a sewing machine, a reciprocating tubular needle bar, a needle-holding slide carried by the needle bar and adapted to reciprocate transversely thereof in a rectilinear line, a rod extending within the tubular 20 needle bar and adapted to reciprocate therewith but capable of an oscillatory movement relatively to the needle bar and engaging at its lower end the upper surface of said needle holding slide, said needle holding slide being provided at its portion 25 engaged by said rod with a transverse slot at right angles to the rectilinear movement of said needle holding slide, said rod being provided with an eccentrically located 30 projection extending parallel to the axis of the rod and in pivotal and sliding direct engagement with the needle-holding slide, and means for causing said rod to oscillate whereby rectilinear movement is imparted 35 to said slide, the rectilinear movement of said slide being equal to the length of the space bounded by lines at right angles to the rectilinear movement of said slide and passing through the center of said projection at 40 its extreme positions.

24. In a sewing machine, a reciprocating needle bar, a needle-holding slide carried by the needle bar and adapted to reciprocate transversely thereof in a rectilinear line, 45 said slide being provided with a guideway extending in a plane perpendicular to the path of the needle bar's reciprocation, said guideway being further perpendicular to the direction of the transverse movement of the needle-holding slide, a member mounted to reciprocate with the needle bar yet capable of turning relatively thereto and engaging at its lower end the upper surface of 50 said needle holding slide, said needle holding slide being provided at its portion engaged by said member with a transverse slot at right angles to the rectilinear movement of said slide, said member being provided with an eccentrically located projection extending into said guideway of the needle-holding slide to a pivotal and sliding direct engagement therewith, and means for causing 55 said member to oscillate whereby rectilinear movement is imparted to said slide,

the rectilinear movement of said slide being equal to the length of the space bounded by lines at right angles to the rectilinear movement of said slide and passing through the center of said projection at its extreme positions. 65

25. In a sewing machine, a reciprocating needle, a looper mounted to turn about an axis which lies always in the same plane with the path of the reciprocating needle, means to shift the needle toward and from the 70 looper in said plane containing the looper axis, a thread catcher lying normally at one side of said plane and idle when the path of the reciprocating needle is close to the looper, and means for operating the thread catcher to take the thread from the needle when the latter reciprocates farther away from the looper and to transfer this thread from the needle to the looper. 75

26. In a sewing machine, a reciprocating needle movable laterally with reference to the path of its reciprocation, in a plane containing the several positions of the needle, a looper mounted to turn about a fixed axis contained in said plane and parallel to the paths in which the needle reciprocates, and a movable thread catcher arranged to transfer the thread from the needle to the looper when the path of the needle is far from the looper. 80

27. In a sewing machine, a reciprocating needle movable laterally with reference to the path of its reciprocation, in a plane containing the several positions of the needle, a looper mounted to turn about a fixed axis contained in said plane and parallel to the paths in which the needle reciprocates, and a movable thread catcher pivoted to swing in a plane perpendicular to said plane and arranged to transfer the thread from the needle to the looper. 85

28. In a sewing machine, a vertically reciprocating needle movable laterally with reference to the path of its reciprocation, in a vertical plane, a looper mounted to turn about a fixed vertical axis contained in said plane, and a thread catcher pivoted to swing in a vertical plane perpendicular to the first-named plane and arranged to transfer the thread from said needle to the looper. 90

29. In a sewing machine, a reciprocating needle bar having a straight longitudinal slot, a needle connected with said bar to reciprocate therewith yet shiftable laterally in relation thereto, a member associated with the needle bar and held to reciprocate therewith yet adapted to turn relatively thereto, said member being provided with a longitudinal cam slot, an operating member, held from following the needle bar and associated turning member in their reciprocating motion, and movable into one or both of said slots, and means connecting the said turn- 95

ing member with the needle to cause a lateral movement of the needle.

30. In a sewing machine, a reciprocating needle movable laterally with reference to the path of its reciprocation, a looper mounted to turn about a fixed axis parallel to the needle, a pivoted thread catcher, a spring acting to hold said thread catcher away from the needle while the latter is reciprocating in operative relation to the looper, and a rotary member acting on the thread catcher in opposition to the spring to bring the thread catcher into operative relation to the needle when the latter is reciprocating out of operative relation to the looper.

31. In a sewing machine, a reciprocating needle shiftable laterally with reference to the path of its reciprocation, a looper mounted to turn about an axis parallel to the needle, and a thread catcher operating to transfer the thread from the needle to the looper.

32. In a sewing machine, a reciprocating needle shiftable laterally with reference to the path of its reciprocation, a looper mounted to turn about an axis parallel to the needle, and a thread catcher movable in a plane perpendicular to the plane in which the looper turns, and operating to transfer the thread from the needle to the looper.

33. In a sewing machine, a reciprocating needle shiftable laterally with reference to the path of its reciprocation, means controlled by the operation of the sewing machine, for effecting such lateral shifting of the needle, a looper co-operating with the needle but independent of its lateral shifting movement, a thread catcher co-operating with said needle and looper to transfer thread from the needle to the looper when the needle reciprocates in a path out of operative relation to the looper, and a device, connected with said looper and said thread catcher, for adjusting these two elements simultaneously in a direction transverse to the path of the needle.

34. In a sewing machine, a reciprocating needle shiftable laterally with reference to the path of its reciprocation, means, controlled by the operation of the sewing machine, for effecting such lateral shifting of the needle, a looper co-operating with the needle but independent of its lateral shifting movement, a thread catcher co-operating with said needle and looper to transfer thread from the needle to the looper when the needle reciprocates in a path out of operative relation to the looper, a cloth-feeder co-operating with said needle, and a device, connected with said looper, thread catcher, and cloth-feeder for adjusting these three elements simultaneously in a direction transverse to the path of the needle.

35. In a zig-zag sewing machine, cutting knives adapted to cut a strip of material, means for feeding an auxiliary material to said cut material in such a position that said auxiliary material will overlap the cut edge of said cut strip of material, means for turning down the margin of said cut strip of material preliminary to the sewing operation for a zig-zag stitching adapted to overwhip said turned down margin upon the under side of said cut strip of material.

36. In the art of machine sewing with zig-zag stitches, in which a continuous overwhipped zig-zag thread is applied above the material, and looped at its apices about a continuous overwhipped zig-zag thread applied below the material, that step which consists in feeding auxiliary material upon a strip of material, the edge of said auxiliary material overlapping the edge of said strip of material, folding the margin of said strip of material till the margin stands about at right angles to the body of the strip, and stitching said strip of material and said auxiliary material together by stitches passing through said strip of material outside of said auxiliary material and through said auxiliary material outside of the fold of said strip of material, the overwhipping of the said threads applied below the material completing the folding of said partly folded margin upon the strip of material.

37. In a zig-zag lock stich sewing machine, the combination of a reciprocating and laterally movable needle, a hooked looper mounted for rotation around a fixed axis parallel to the needle and toward and from the hook of which the needle is movable, and means co-operating with the needle to catch the thread and transfer it to the hook of the looper during the reciprocation of the needle when remote from the looper.

38. In a sewing machine, the combination of a reciprocating and laterally movable needle, a hooked looper mounted for rotation around a fixed axis parallel to the needle, means for moving the needle laterally toward and from the hook of the looper during alternate reciprocations, the hook of the looper co-operating directly with the needle at one reciprocation, and means including a normally stationary member having a point moving into co-operation with the needle at the next reciprocation to catch the thread and transfer the same to the looper hook.

39. In a lock stitch sewing machine, the combination with a pair of hooked loopers for rotation around parallel vertically fixed axes, a reciprocating needle bar having its axis between and parallel with the axes of the loopers, a pair of needles carried by the needle bar, means for moving the needles

toward and from each other, whereby they co-operate with the looper hooks at one reciprocation, and means co-operating with the needles when moved away from the looper hooks to catch the threads and transfer the same to the looper hooks.

40. The combination with a sewing machine bed plate having a plurality of binding screws tapped therein, a pair of bearing

blocks having slots through which said 10 screws project and along which the blocks are adjustable toward and from each other, means to tighten or loosen all of said screws simultaneously, and loopers mounted upon said blocks and adjustable therewith toward 15 and from each other.

RALPH M. SHARAF.
